UNITED STATES PATENT OFFICE

2,128,794

LIQUID COOLER

Ralph E. Billings, Fort Wayne, Ind., assignor to
General Electric Company, a corporation of
New York

Application March 26, 1937, Serial No. 133,217

7 Claims. (Cl. 62—141)

My invention relates to mechanically refrigerated liquid coolers for cooling drinking water or other liquids.

It is an object of my invention to provide an improved arrangement for controlling the admission of liquid refrigerant into a refrigerant evaporator of a liquid cooler and for preventing flooding of the evaporator with liquid refrigerant and withdrawal of liquid refrigerant therefrom into a refrigerant liquefying unit associated therewith.

Another object of my invention is to provide an improved control arrangement for liquid coolers, which is effective in operation, simple and compact in structure and economical in construction.

Further objects and advantages of my invention will become apparent as the following description proceeds, and the features of novelty 20 which characterize my invention will be pointed out with particularity in the claims annexed to and forming a part of this specification.

For a better understanding of my invention reference may be had to the accompanying drawing 25 in which the single figure is an elevational view, partly in section, of a liquid cooler embodying my invention, and a diagram of a refrigerant liquefying unit associated with a refrigerant evaporator arranged in the liquid cooler.

Referring to the drawing, I have shown a liquid cooler having a vertically disposed cylindrical casing 10 forming a liquid chamber 11 therein. Preferably, the casing 10 is made of 35 sheet steel and includes a cylindrical side wall 12, an inwardly concave top wall 13 and an outwardly convex bottom wall 14, the peripheral edges of the top and bottom walls being flanged and welded to the adjacent end edges of the cylindrical side wall 12. This construction of the 40 casing 10 permits liquid under relatively high pressure to be stored safely in the liquid chamber 11. A refrigerant evaporator 15 is disposed within the liquid chamber 11 for cooling the liquid stored therein and comprises spaced-apart inner and outer helical coils 16 and 17 respectively, which are connected in series at their lower ends. Preferably, the inner and outer coils 16 and 17 are formed from a single length of 45 conduit, and they are wound in opposite directions to provide maximum contact with the surrounding liquid in the liquid chamber 11. The outer coil 17 is provided with an inlet end 18 which extends through and is secured in an opening 19 in the top wall 13 of the casing 10. The

outer coil 17 extends from the upper portion of the liquid chamber 11 downwardly to the lower portion thereof where it communicates with the inner coil 16. The inner coil 16 extends from the lower portion of the liquid chamber 11 upwardly to the upper portion thereof and then downwardly to the lower portion thereof. The inner coil 16 is provided with an enlarged outlet end 20 which extends from the lower portion of the liquid chamber 11 upwardly through the upper portion thereof, and is secured in an opening 21 in the top wall 13 of the casing 10.

The inlet end 18 of the outer coil 17 is connected to a liquid refrigerant supply conduit 22 through an automatic thermostatic expansion valve 23 which controls the admission of liquid refrigerant thereto. The automatic thermostatic expansion valve 23 is of the conventional type and throttles the flow of liquid refrigerant into the outer coil 17 and includes a thermostatic element or bulb 24 connected to the automatic thermostatic expansion valve 23 by a conduit 25. The thermostatic bulb 24 contains a fluid, such as sulphur dioxide. The outlet end 20 of the inner coil 16 is closed by a fitting 26 which is connected to a refrigerant suction conduit 27. A conduit 28 extends through an opening in the top wall of the fitting 26 into the interior of the enlarged outlet end 20 of the inner coil 16 and is provided with a closed end forming a well 29 therein 30 disposed adjacent the lower portion of the liquid chamber 11 and arranged in good heat exchange relationship with the vaporized refrigerant in the enlarged outlet end 20 of the inner coil 16. The thermostatic bulb 24 for controlling the automatic thermostatic expansion valve 23 is positioned in the well 29 in good heat exchange relationship therewith.

The liquid to be cooled, such as drinking water or the like, is supplied to the upper portion of the 40 liquid chamber 11 under pressure through a supply conduit 30 secured in an opening 31 in the top wall 13 of the casing 10. The liquid supplied to the liquid chamber 11 is stored therein under pressure and withdrawn from the lower portion 45 thereof after it has been cooled through a withdrawal conduit 32 secured in an opening 33 in the top wall of the casing 10. It will be observed that the inlet end of the liquid withdrawal conduit 32 is arranged on the opposite side of the 50 liquid chamber 11 from the outlet end of the liquid supply conduit 30. Thus, the liquid from the supply conduit 30 flows downwardly and through the helical coils 17 and 16 in substantial- 55 ly a sinuous path to the liquid withdrawal con-

duit 32, this sinuous path of the liquid flowing through the helical coils 17 and 16 being produced by the opposite inclination of these coils due to the fact that they are wound in opposite directions. As the liquid in the liquid chamber 11 is cooled, it gravitates to the lower portion thereof forming a zone of relatively cool liquid. As the relatively warm liquid is supplied to the upper portion of the liquid chamber 11, the relatively cool zone of liquid in the lower portion thereof is intermixed only slightly therewith.

The casing 10, the connections between various conduits and the casing 10, and the automatic thermostatic expansion valve 23 are surrounded by a suitable layer of heat insulation 34 and enclosed in an outer shell 35. The outer shell 35 includes a cylindrical side wall 36 and removable ends 37, the ends 37 being removable to facilitate inspection of the liquid cooler and adjustment of the automatic thermostatic expansion valve 23.

During operation of the liquid cooler illustrated, liquid refrigerant is supplied to the inlet end 18 of the outer coil 17 from the liquid refrigerant supply conduit 22 through the automatic thermostatic expansion valve 23. The liquid refrigerant is vaporized in the coils 17 and 16 by the absorption of heat from the surrounding liquid in the liquid chamber 11, and with- drawn from the enlarged outlet end 20 of the inner coil 16 through the fitting 26 through the refrigerant suction conduit 27. Liquid refrigerant is supplied to the liquid refrigerant supply conduit 22 and vaporized refrigerant is with- drawn from the refrigerant suction conduit 27 by a refrigerant liquefying unit including a refrigerant compressor 38 and a refrigerant condenser 39. The compressor 38 is connected to the refrigerant suction conduit 27 and is driven by an electric motor 40 by a belt 41 arranged be- tween a pulley 42 carried by the shaft of the electric motor 40 and a flywheel 43 carried by the shaft of the compressor 38. The compressor is of the reciprocating type and compresses the vaporized refrigerant and discharges the same into the condenser 39, wherein it is liquefied and delivered to a liquid receiver 44 connected to the liquid refrigerant supply line 22. The electric motor 40 is connected to a suitable source of supply 45 by a pair of leads 46 and 47, an electric switch 48 being arranged in the lead 47 to control the circuit of the electric motor 40. The electric switch 48 is controlled by an ex- pansible bellows 49 mounted upon a support 50 and connected by a conduit 51 to a thermostatic element or bulb 52 arranged in good heat ex- change relationship with the liquid stored in the liquid chamber 11. The bulb 52 contains a fluid, such as sulphur dioxide, and is positioned in a well 53 formed in the closed end of a conduit 54, the conduit 54 extending through and being se- cured in an opening 55 in the top wall 13 of the casing 10. When the temperature of the liquid stored in the liquid chamber rises to a prede- termined temperature the fluid in the thermo- static bulb 52 expands sufficiently to actuate the bellows 49 and close the electric switch 48 to start the electric motor 40. The refrigerating cycle above described is continuously repeated until the liquid stored in the liquid chamber 11 is cooled to a predetermined temperature. The fluid in the thermostatic bulb 52 then contracts sufficiently to actuate the bellows 49 and open the electric switch 48 to stop the electric mo-

The disposition of the well 29 within the enlarged outer end 20 of the inner coil 16 and ad- jacent the lower portion of the liquid chamber 11 and the arrangement of the thermostatic bulb 24 therein for controlling the automatic ther- mostatic expansion valve 23 is very important as a substantial improvement in the operation of the liquid cooler is obtained thereby. The ar- rangement of the thermostatic bulb 24 in the well 29 formed in the closed end of the conduit 28 and the arrangement of the conduit 28 in the outlet end 20 of the inner coil 16 where it is surrounded by the vaporized refrigerant there- in is effective to produce a very accurate control of the automatic thermostatic expansion valve 23 in response to the temperature of the vapor- 10 ized refrigerant in the outlet end 20 of the inner coil 16, there being a small temperature differ- ence between the vaporized refrigerant and the fluid contained in the thermostatic bulb 24. 20

The well 29 is arranged in the enlarged outlet end 20 of the inner coil 16 and disposed in the well 29 in the lower portion of the liquid chamber 11 and the thermostatic bulb 24 is positioned therein so that the operation of the thermostatic 25 bulb 24 will not be appreciably affected by the temperature of the relatively cool zone of liquid in the lower portion of the liquid chamber 11. The thermostatic bulb 24 is not appreciably af- fected by the temperature of this zone of liquid 30 because the temperature of this zone closely par- allels the saturation temperature of the vapor- 35 ized refrigerant in the enlarged outlet end 20 of the inner coil 16. Thus, the thermostatic bulb 24 accurately controls the automatic thermostat- 40 ic expansion valve 23 in response to the tempera- ture of the vaporized refrigerant in the enlarged outlet end 20 of the inner coil 16. The admis- sion of liquid refrigerant into the evaporator 15 is thus properly controlled in spite of variations 45 in the temperature of the liquid supplied to the liquid chamber 11 through the supply conduit 30 and in ambient temperature, and there is no flooding of the evaporator 15 or withdrawal of liquid refrigerant therefrom through the refrig- 45 erant suction conduit 27 into the refrigerant liquefying unit.

While I have shown a particular embodiment of my invention in connection with a liquid cooler refrigerated by a refrigerating machine of the 50 compression type, I do not desire my invention to be limited to the particular construction shown and described, and I intend in the appended claims to cover all modifications within the spir- 55 it and scope of my invention.

What I claim as new and desire to secure by Letters Patent of the United States, is:

1. A liquid cooler including a casing forming a liquid chamber, means including a refrigerant evaporator for cooling the liquid therein, means for supplying liquid refrigerant to said evap- 60 orator, means including an expansion valve lo- cated at the inlet of said evaporator for con- trolling the admission of refrigerant thereto, and means including a thermostatic element disposed within said chamber adjacent the lower portion thereof and arranged in the outlet of said evap- 65 orator in good heat exchange relationship with the vaporized refrigerant therein for controlling the expansion valve.

2. A liquid cooler including a casing forming a liquid chamber, means including a refrigerant evaporator for cooling the liquid therein, means for supplying liquid refrigerant to said evap- 70 orator, means including an expansion valve lo-

- cated at the inlet of said evaporator for controlling the admission of refrigerant thereto, a conduit extending into said evaporator and having a well therein disposed adjacent the lower portion of said chamber, said well being arranged in good heat exchange relationship with the vaporized refrigerant in the outlet of said evaporator, and means including a thermostatic element positioned in said well for controlling said 10 expansion valve.
3. A liquid cooler including a casing forming a liquid chamber, means including a refrigerant evaporator for cooling the liquid therein, means including a refrigerant liquefying unit for supplying liquid refrigerant to said evaporator, means including an expansion valve located at the inlet of said evaporator for controlling the admission of refrigerant thereto, means including a thermostatic element disposed within said chamber adjacent the lower portion thereof and arranged in the outlet of said evaporator in good heat exchange relationship with the vaporized refrigerant therein for controlling said expansion valve, and means including a second thermostatic 20 element responsive to the temperature of the liquid in said chamber for controlling the operation of said refrigerant liquefying unit.
4. A liquid cooler including a casing forming a liquid chamber, means including a refrigerant coil for cooling the liquid therein, means for supplying liquid refrigerant to said coil, means including an expansion valve located at the inlet end of said coil for controlling the admission of refrigerant thereto, the outlet end of said coil being enlarged, and means including a thermostatic element disposed within said chamber adjacent the lower portion thereof and arranged in the enlarged outlet end of said coil in good heat exchange relationship with the vaporized refrigerant therein for controlling said expansion 30 valve.
5. A liquid cooler including a casing forming a liquid chamber, means including a refrigerant coil for cooling the liquid therein, means for supplying liquid refrigerant to said coil, means including an expansion valve located at the inlet end of said coil for controlling the admission of refrigerant thereto, the outlet end of said coil
- being enlarged, a conduit extending into the enlarged outlet end of said coil and having a well therein disposed adjacent the lower portion of said chamber, said well being arranged in good heat exchange relationship with the vaporized 5 refrigerant in the outlet end of said evaporator, and means including a thermostatic element positioned in said well for controlling said expansion valve.
6. A liquid cooler including a vertically disposed casing forming a liquid chamber, means for supplying liquid to the upper portion of said chamber, means for withdrawing liquid from the lower portion of said chamber, means including a refrigerant evaporator for cooling the liquid 15 therein, means for supplying liquid refrigerant to said evaporator, means including an expansion valve located at the inlet of said evaporator for controlling the admission of refrigerant thereto, and means including a thermostatic element disposed within said chamber adjacent the lower portion thereof and arranged in good heat exchange relationship with the vaporized refrigerant in the outlet of said evaporator for controlling said expansion valve.
7. A liquid cooler including a vertically disposed casing forming a liquid chamber, means for supplying liquid to the upper portion of said chamber, means for withdrawing liquid from the lower portion of said chamber, means including a refrigerant coil for cooling the liquid therein, means including a refrigerant liquefying unit for supplying liquid refrigerant to said coil, means including an expansion valve located at the inlet end of said coil for controlling the admission 35 of refrigerant thereto, the outlet end of said coil being enlarged, means including a thermostatic element disposed within said chamber adjacent the lower portion thereof and arranged in the enlarged outlet end of said coil in good heat 40 exchange relationship with the vaporized refrigerant therein for controlling said expansion valve, and means including a second thermostatic element responsive to the temperature of the liquid in said chamber for controlling the operation of said refrigerant liquefying unit.

RALPH E. BILLINGS.
